FRANCESCO RENZO AND RICHARD SEDLATSCHEK, OF PATERSON, NEW JERSEY.

SHUTTLE.

Application filed April 14, 1928. Serial No. 269,929.

This invention relates to shuttles and it has for its object to provide a shuttle with a tension device whereby the threading can be accomplished by entry of the thread or filling 5 transversely of itself and as an incident to automatic replenishing of the filling supply and to produce a shuttle of this kind which will operate at all times with reliability and can be made at little expense and whose parts 10 permit ready access thereto for adjustment, replacement or repairs.

In the drawing,

Fig. 1 is a fragmentary plan of the improved shuttle;

15 Fig. 2 a section on line 2—2, Fig. 1;

Fig. 3 is a fragmentary side elevation thereof;

Fig. 4 an isometric view of the tension device, removed;

20 Fig. 5 an end elevation thereof;

Fig. 6 a section of the shuttle on line 6—6,

Fig. 2;

Fig. 7 a section of said device on line 7—7,

Fig. 5;

25 Fig. 8 a view of the tension lever.

The shuttle body 1 has the usual cavity 2 for the filling package 3, the same being extended at 4 forward and being open at the top as usual.

30 There is also in the top of the shuttle a channel 5 leading forward from the cavity 2—4 and adapted to permit the filling to enter downwardly into the cavity. At the near side of the body 1 in Fig. 1 is the filling outlet

35 6 with which communicates, reaching downwardly from the top of the shuttle, a slit 7, whereby when the filling is formed in a bight, as will hereinafter appear, it obtains access to the outlet.

40 The improved tension device comprises two principal parts, a housing and a tension lever—the latter being elastically controlled. The construction and arrangement of these parts are the factors resulting in producing a shuttle of the present kind which is at once efficient in operation, simple and inexpensive in construction and capable of being readily kept in good working order. The housing, 45 8, is struck up from a sheet metal blank so as to produce a bottom wall 8^a, two side walls 8^b, an open front end, a rear wall 8^c and a top wall 8^d. The top and rear walls are constructed to permit the filling to enter downward into the housing, thereupon to reeve 50 through the same on being drawn from the package 3, and thereafter retain it therein,

thus: The top wall, which is a bent-off extension of the near side wall 8^b in Fig. 1 and overhangs the space of the housing, is formed with two tongues 9 and 10, both extending 55 short of the other side wall so as to expose from above a part of the bottom wall and other elements and to permit the filling to enter the housing as stated. Tongue 9 is curved gradually downward into the space of the 60 housing, its extremity being returned in the general direction of the near side wall in Fig. 1. Tongue 10 is bent vertically downwardly at its extremity, thus forming a hook 10^a whose forward edge is rearwardly inclined; the forward edge 10^b of tongue 10 is aligned with the rear side of slit 7, being spaced from the part 11 of the shuttle body opposite it so that said slit is thus in effect extended 65 inward. The rear wall 8^c has a hole 12 therein to which enters sidewise thereof and from the top of the wall a narrow passage 12^a, and tongue 9, it will be noted, crosses this passage viewing the device longitudinally (Figs. 5 and 6). If the filling, extending from the 70 package 3 forward, be at a point forward of the hole 12 held downwardly it will enter said hole by the passage; and as it is drawn from the package and undergoes a consequent twirling it will be confined by the hole 75 80 against undue ballooning. If the passage 12^a is suitably narrow and enters the hole laterally thereof as shown the filling in reeveing through the hole will be confined therein without the tongue 9, which is not therefore 85 an indispensable element of the device. 90

The tension lever is a length of wire 13 and is formed as follows: It has a bearing coil 13^a from which at one end thereof the wire extends to form an arm 13^b and from which at the other end thereof extends the main arm of the lever, the same being substantially straight. When positioned in the shuttle the coil 13^a rests on the bottom wall 8^a of the housing and near the far side wall 8^b and the end wall 8^c with its axis vertical; 14 is a fulcrum screw tapped into the bottom wall through the coil. Arm 13^b of the lever projects through a hole 15 in the housing and into a cavity 16 at the side of the shuttle and in this cavity is an elastic 17 which connects said arm with an adjusting screw 18 driven into the shuttle body. The main arm of the lever, when the latter is in its normal position, held by the elastic 17, extends toward the right hand end of the shuttle and bears 100 against the far side wall 8^b. At its free end 105 110

the wire of the lever is bent downwardly and then returned upwardly to form an upwardly opening crotch 13^a, its extremity being again returned downwardly within the crotch, as at 5 13^b. The construction is such that when the filling enters downwardly into the shuttle cavity 2—4 to enter the crotch 13^a it cannot become caught between the lever and the far side wall of the cavity but will be shunted 10 into the crotch because the main arm of the lever presents a substantially straight top surface to the stretched filling clear to the free end of such arm.

The housing 8 is secured in the shuttle body 15 by one or more screws 19 which are exposed at the top and therefore freely accessible, so that the device can readily be removed for repairs.

While, further, the filling has ready access 20 downward to the tension lever when the threading operation is performed, the tension lever is easily removed for adjustment or replacement and its fulcruming screw 14 is also readily accessible without disturbing the 25 housing in either case.

The filling is entered into the control of the tension device by stretching it across the top of the shuttle to the right thereof and then causing a movement, one relatively to and past the other, with respect to the shuttle and the point to which the filling is held, so that 30 a bight is formed in the filling which then enters via the slit into the outlet 6, the result being that the filling is received in the crotch 35 13^a of the tension lever and enters the hole 12 in the rear wall of the housing and also becomes caught under the tongue 10, to thereupon be retained by its hook 10^a. This would be the operation if, on automatic replenishing 40 of the filling in the shuttle when in the right hand box of the loom, the shuttle performed its first traverse to the left with the filling secured to some part of the loom and then, a new shed having been formed, the shuttle performed its next traverse to the right.

Having thus fully described our invention, what we claim is:

1. A shuttle having an upwardly open cavity to receive a filling package, a filling outlet extending from the cavity through one side wall of the shuttle and between the received package and one end of the shuttle, a filling-catching tongue overhanging from said wall a part of the cavity and leaving the

remainder thereof upwardly exposed, and a 55 top slit communicating with the outlet between the tongue and said end of the shuttle, in combination with a tension lever movable within the cavity toward said wall under the tongue and from the opposite wall and normally held toward the latter and having an upwardly open filling-receiving crotch normally exposed from above, and a screw withing the cavity forming the fulcrum for the lever and screwed downwardly into the shuttle in said exposed part of the cavity.

2. A shuttle comprising a body having an upwardly open cavity to receive a filling package, a housing removably arranged in the cavity between the received package and one end of the body and having a bottom wall and a portion upstanding therefrom and provided with a filling-catching tongue overhanging a part of said wall and leaving the remainder thereof upwardly exposed, the shuttle having a lateral filling outlet and a top slit communicating therewith between the tongue and said end of the body, a tension device for the filling movable within the housing and adapted to be engaged by the filling when the same is caught by the tongue, and a screw securing the housing in the body and driven through said exposed part of said wall from above and downwardly into the body.

3. A shuttle having an upwardly open cavity to receive a filling package, a filling outlet extending from the cavity through one side wall of the shuttle and between the received package and one end of the shuttle and means to admit the filling into and thereupon confine the filling in said outlet, in combination with a tension lever arranged within said cavity and movable toward and from said wall and normally held toward the opposite wall of the shuttle, and a fulcrum device on which said lever is fulcrumed and from which it projects toward said end of the shuttle, said lever being substantially straight from its fulcrum to its free end and having at said free end a depending portion forming an upwardly open crotch adapted to receive the filling when entered downwardly into the cavity.

In testimony whereof we affix our signatures.
